CLAIM

The ornamental design for a three wheeled pedal driven vehicle, as shown.

DESCRIPTION

FIG. 1 is a front perspective view of a three wheeled pedal driven vehicle showing my new design;

FIG. 2 is a rear perspective view thereof;

FIG. 3 is a side elevation view thereof;

FIG. 4 is a front elevation view thereof;

FIG. 5 is a top plan view thereof;

FIG. 6 is a elevation view thereof, of a side opposite the side shown by FIG. 3;

FIG. 7 is a rear end elevation view thereof; and

FIG. 8 is a bottom plan view thereof.
